TRESTLE

Clinton H. Bond, Cedar Falls, Iowa, assignor to
 Wagner Manufacturing Company, Cedar Falls,
 Iowa, a corporation of Iowa

Application October 21, 1939, Serial No. 300,680

2 Claims. (Cl. 304—5)

My invention relates to improvements in trestles, and an object of my improvements is to furnish in such a device, a like associated pair of medially hinged legs or standards, with upper terminal and cooperating gripping means for a wooden beam seated between them for penetration thereof at opposite sides, and with laterally oppositely directed parallel clamping members to embrace the beam between them to prevent looseness or rocking movements between the terminations of the beam and the clamping members.

Another object is to locate pluralities of such penetrating means above and below said clamping members respectively, to reinforce each other in combination with said members to together assure rigidity of the joints between the beam ends and said penetrating and clamping devices.

I have in actual practice accomplished the above purposes, and by the means which are hereinafter illustrated in the accompanying drawings, described in the specification and claimed in the claims.

Fig. 1 is an end elevation of one of the trestle supporting devices with the lower parts of its limbs spread apart by limiting collapsible connections, and with their upper gripping and penetrating parts rigidly seating between them terminally an end of a wooden reach or beam, releasably.

Fig. 2 is a like elevation of one of the supporting devices as collapsed. Fig. 3 is a side elevation of one of the limbs, with upper end contacting a beam part. Fig. 4 is an inner face elevation of one of the limbs. Fig. 5 is a plan view of the under face of one of the flat discoidal terminations of the limb ends. Fig. 6 is a modification of the arm hinging means.

Referring to said Figs. 1 and 2, the numerals 1 and 1a denote like but relatively reversed leg members, preferably as shown inwardly troughed of metal for lightness and rigidity. To prevent injury to a floor or subsidence into an earthy base, these leg members are provided with flat discoidal bases 2 and 2a respectively, alike, but the lower ends of the troughed leg members are beveled, so that when the legs are spread apart as in Fig. 1, the parts 2 and 2a are in horizontal alinement.

The leg members 1 and 1a are preferably hingedly connected together substantially medially of their length, by arm sections 3 and 3a thereacross, having their outer ends pivoted to these members as at 4 and 4a. The inner ends of the members overlap and are connected by a

5 bolt and nut at 8, the latter having opposite arms 9. As shown in Fig. 2, when the members 1 and 1a are brought into close proximity, a rectangular notch 3b in the arm 3a seats within it a fixed pin 3c on the other arm member 3. When the members 1 and 1a are spread apart as in Fig. 1, the pin 3c stops the arms 3 and 3a horizontally against downward subsidence.

The upper parts of the members 1 and 1a are 10 pivoted together at 5 at overlapped shoulders. Above the shoulders the side walls of 1 and 1a are cut back and shaped along their opposed edges with medial projections 6 and 6a in alignment at right angles with said members projecting oppositely and have holes 6b (see Figs. 3 and 4) through which nails or screws may be passed if necessary. Above and below these projections 6 and 6a the inner edges of the members have pluralities of teeth 7 and 7a respectively. In Fig. 1 is shown an end part of a horizontal wooden beam 10 which seats in the hollow of the members 1 and 1a of a spaced pair of the devices, whereby when the members 1 and 1a are 15 spread apart below, the teeth 7 and 7a penetrate the opposite sides of the beam 10, at the same time that the flat projections 6 and 6a compressingly contact flatly with the opposite side faces of the beam. These projections in extending oppositely along the beam, prevent rocking 20 of the members in said seat, so that the teeth and projections together stabilize the ends of the beam in the seat. The trestle thus supplied will sustain heavy loads, and resist torsional strains 25 while in use, without coming apart.

If desired, a pad, flat or cupped, made of rubber or other yielding material may be seated 30 about the discoidal terminal parts 2a to prevent scratching of a floor or sliding of the device.

The trestle thus supplied will support itself 35 under strain in use, and the end devices when removed from the beam, may be collapsed and stacked in small compass for storage or transportation, or used together with another beam.

In Fig. 6 is shown a modification of the hinged joint between the arms 3b and 3c. The inner ends, overlapped, of said arms are pivoted together by a pintle 11. Semicircular notches 13 and 13a are provided in the lower edges of 40 arm 3c equidistantly oppositely from the pintle 11, and a short stud 12 is fixed on the arm 3b to extend into the notch 13 on the arm 3c when the legs 1 and 1a are spread apart, thus locking the arms together beyond a dead center, and 45 against collapsing or subsiding downwardly.

When the legs 1 and 1a are collapsed together, the stud 12 seats in the notch 13a, whereby the legs 1 and 1a are locked in their upward position. The stud 12 is short, flat, and the stud springs into either notch position due to the resiliency of the arms permitting enough spreading to allow the stud to spring into either notch when the legs are either extended into alignment, as shown in Fig. 6, or when the legs are brought together, respectively.

In Fig. 6, I have shown also, disks of rubber or other substance of yielding character at 2b secured on the discoidal metal feet 2 and 2a by rivets or other means of fastening. The pads thus furnished may be of any other shape desired, and may be of larger diameter than the feet 2 and 2a, or may be secured upon said feet by turned rims or other means.

I claim:

1. In a device of the character described, a pair of leg members having their upper parts pivoted together a distance below their terminations, said terminations having inwardly directed spaced pluralities of detents for gripping a body between them, and hinging arms whose outer ends are pivoted respectively to opposite medial parts of said members and having their

inner ends overlapping and pivoted together, one arm having downwardly opening recesses positioned at opposite sides of their pivotal connection and equidistantly therefrom, and a stud on the other arm spaced from said pivot and adapted to enter one or the other recess when said leg members are either spread apart beyond a dead center, or when the arms are collapsed together upwardly.

2. In a device of the character described, a beam, a pair of leg members having their upper parts pivoted together a distance below their terminations, said terminations having spaced serrated facing edges for gripping the beam between them, said members having apertured oppositely directed alined wings, clasping the opposite upper parts of the leg members between them, hinging arms whose outer ends are pivoted respectively to opposite medial parts of said members with their inner ends overlapping and pivoted together beyond or on a dead center, the lower part of one arm having spaced recesses at opposite sides of and equally spaced from the pivotal connection, and a lateral stop on the other arm releasably seating in the outermost recess of the first arm when both are extended.

CLINTON H. BOND.
